UNITED STATES PATENT OFFICE.

WILLIAM M. DEHN, OF SEATTLE, WASHINGTON.

PRIMARY DETONATING COMPOSITION.

1,404,687.

Specification of Letters Patent. Patented Jan. 24, 1922.

No Drawing.

Application filed May 27, 1920. Serial No. 384,734.

To all whom it may concern:

Be it known that I, WILLIAM M. DEHN, a citizen of the United States, residing at Seattle, in the county of King and State of Washington, have invented certain new and useful Improvements in Primary Detonating Compositions, of which the following is a specification.

This invention refers to the use of diazodinitrophenol (4,6-dinitro-2-diazophenol) as a substitute capable of replacing the fulminates, the azides, or other detonating compounds hitherto used in primary detonating charges.

15 I have found that diazodinitrophenol possesses a number of properties that characterize it as an excellent detonating explosive.

It contains no metals. Metallic compounds of hydrazoic and fulminic acids have 20 been used almost universally as "the explosive of the first class" in primer charges; that is to say, as the compound which is capable of causing the detonation of other explosives in contact therewith when it itself is 25 ignited or is subjected to percussion. Non-metallic primers have met with little use for reasons of high cost, low brisance, unfavorable temperatures of melting and ignition, or undependable sensitiveness to shock. 30 Diazodinitrophenol is free from these objections, hence can be used for general primary detonating charges and for special primary detonating charges designed to avoid fouling and amalgamating the metals of 35 ordnance.

When exploded by itself, diazodinitrophenol gives free carbon and combustion products substantially in accordance with the equation:

However, when exploded in the presence of ammonium nitrate it gives smokeless combustion products, substantially in accordance 45 with the equation:

When exploded in the presence of the chlorates or the perchlorates of the alkali metals, 50 it gives smoke composed of alkali chlorides which have little or no corrosive effects on metals of ordnance. Therefore, oxidizing accelerators may be used with diazodinitrophenol to form detonating compositions free 55 from mercury, lead and other heavy metals.

The high capacity of diazodinitrophenol

for oxygen is a great advantage because large percentages of inexpensive oxygen carriers can be used without loss of detonating power in the resulting compositions. For 60 example, whereas the theoretical percentage of potassium chlorate for mercury fulminate is 22.3 to oxidize to carbon dioxide, with common oxidizing salts for diazodinitrophenol the percentages are 60 to 75 to oxidize 65 to carbon dioxide, and 28 to 43 to oxidize to carbon monoxide. From these values it may be observed that primary detonating charges compounded of diazodinitrophenol and oxidizing salts may be varied widely according 70 to requirements.

Another great advantage of diazodinitrophenol is its indifference toward water, as is evidenced by its non-hygroscopic nature and by its chemical stability when stored in 75 water. This property permits of long storage, of its compositions, without loss of power, a contradistinction to mercury fulminate which is especially subject to deterioration in moist air. Furthermore its 80 non-hygroscopic nature requires no protecting admixed or superimposed materials and no special precautions for storage.

Diazodinitrophenol is stable in the presence of acids, hence nitric acid and its decomposition products, which may be evolved spontaneously from explosive compositions during storage, have little or no hazardous effects upon it.

Diazodinitrophenol can be safely and powerfully compressed without loss of sensitiveness to explode, hence it and its explosive mixtures can be concentrated to favorable densities in detonating containers.

The temperatures of melting and ignition 95 of diazodinitrophenol are above 150 degrees, hence diazodinitrophenol is favorably sensitive to combustion and to percussion.

Diazodinitrophenol can be manufactured cheaply from materials always easily available.

When measured by the sand test, diazodinitrophenol reveals great power of demolition. Small quantities of it superimposed on ordinary explosive compositions cause complete explosions of the same. Its 105 sensitiveness and brisance, therefore, admit of it being used as a substitute for the fulminates, the azides, and the other detonating explosives.

Under varied conditions of granulation, compression, and confinement, I have found

that the strength of pure disazodinitrophenol is invariably greater than that of mixtures of potassium chlorate and mercury fulminate. When mixed with potassium chlorate in advantageous percentages it reveals substantially 40 per cent greater power than the most efficient mixtures of potassium chlorate and mercury fulminate. Even with equal weight of potassium chlorate, diazodinitrophenol yields detonating compositions more powerful than the usual detonating compositions of mercury fulminate. The granulated or powdered mixtures of diazodinitrophenol and potassium chlorate can be made desirably fine grained and free running and can be loaded readily into detonating shells or other containers.

With the most effective masses of other oxidants, such as the nitrates, the perchlorates and the peroxides, compositions are formed whose detonating strengths are substantially similar to the above described mixtures of diazodinitrophenol and potassium chlorate.

Whereas my invention is capable of being carried out in many different ways, it is herein observed that it does not relate to secondary detonating, or "booster" charges, to be exploded by adjacent or superimposed primary detonating charges composed in accordance with my invention; nor does it relate to charges of mercury fulminate, used as an intermediate to this "booster" and this adjacent or superimposed primary detonating charge composed in accordance with my invention.

Whereas my invention is capable of embodiment in many different forms, for the purpose of illustration, I may apply it in the following manners:

A. Pure dry powdered diazodinitrophenol, mixed with a small percentage of potassium chlorate, is run into detonating tubes, casings or caps, and the composition is compressed to the required density.

B. Substantially equal parts of diazoni-

trophenol and potassium chlorate are intimately intermixed and then the mixture is run into detonating tubes, casings or caps and compressed to the required density.

50

C. A mixture of 70 parts of diazodinitrophenol and 30 parts of potassium chlorate is first prepared and then is compressed to the required density in detonating tubes, casings or caps.

55

D. The composition varying within the above described limits may be compressed into tubes, casings or caps previously partly charged with explosive compositions prepared in accordance with my prior process 60 above referred to.

I claim:

1. A primary detonating composition comprising diazodinitrophenol and an oxidizing salt.

65

2. A primary detonating composition comprising diazodinitrophenol and an oxidizing salt of a fixed alkali.

3. A primary detonating composition comprising diazodinitrophenol and an oxidizing 70 salt of potassium.

4. A primary detonating composition comprising diazodinitrophenol and a chlorine-containing oxidizing salt of a fixed alkali.

75

5. A primary detonating composition comprising diazodinitrophenol and a chlorine-containing oxidizing salt of potassium.

6. A primary detonating composition comprising diazodinitrophenol and a chlorate of a fixed alkali.

80

7. A primary detonating composition comprising diazodinitrophenol and the chlorate of potassium.

8. A primary detonating composition comprising diazodinitrophenol and the chlorate 85 of potassium mixed therewith, the detonating charge being highly compressed.

9. A detonator for explosive material comprising diazodinitrophenol.

In witness whereof, I have signed my 90 name hereto.

WILLIAM M. DEHN.
